HOSIERY HANGER

Valentine Samuel Bauman, Des Plaines, Ill.

Application December 17, 1956, Serial No. 44,216

Term of patent 14 years

(Cl. D80—8)

Fig. 1 is a perspective view of a hosiery hanger embodying my design;

Fig. 2 is a front elevational view thereof;

Fig. 3 is a top plan view thereof; and

Fig. 4 is a section thereof taken along lines 4—4 to indicate its thickness.

I claim:

The ornamental design for a hosiery hanger, substantially as shown.
